Primary Examiner — Bridget L Eland*(74) Attorney, Agent, or Firm* — Cantor Colburn LLP(57) **CLAIM**

The ornamental design for a connecting device for wireless communications, as shown and described.

DESCRIPTION

FIG. 1 is a front perspective view of a connecting device for wireless communications, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the connecting device for wireless communications form no part of the claimed design.
